EX

No. 15,135

July 8, 1884

UNITED STATES PATENT OFFICE.

HENRY TEXTOR, OF BROOKLYN, NEW YORK, ASSIGNOR TO JAMES S. SIMPSON AND GEORGE F. SIMPSON, BOTH OF SAME PLACE.

DESIGN FOR A NEWEL-POST.

SPECIFICATION forming part of Design No. 15,135, dated July 8, 1884.

Application filed January 5, 1884. Term of patent 7 years.

To all whom it may concern:

Be it known that I, HENRY TEXTOR, of Brooklyn, in Kings county, and the State of New York, have invented and produced a certain new and useful Design for Newel-Posts, of which the following is a specification.

I will describe in detail a newel-post embodying my design, and then point out the characteristic features of the design in claims.

10 The accompanying illustration is a perspective view of a newel-post embodying the design.

A designates the base of the newel. B designates the body. C designates the cap, and D designates the finial. The base A is shown as of rectangular form. At the top it is provided with a bead, a. The body is polygonal. At its corners are pilasters b, which as here shown are round at the upper part and fluted at the lower part. These pilasters have bases which are square and fluted at the lower part, b', and have tapering foliate and fluted upper portions, b''. Between the portions b' b'' of the bases are moldings b''. At the top and bottom of the fluted portions of the pilasters are bands b' b''. The capitals of the pilasters consist of moldings b''. Between the bases of the pilasters are moldings b' b''. In the sides of the body B, between the pilasters, are panels b'', embellished with foliate figures b'''. Above the panels b'' bars b''' extend between the pi-

lasters. Moldings b''' extend around the body above the pilasters, and as here shown have a greater projection at the corners than elsewhere. Above the moldings b''' is a flat-sided portion, b''', from which extend downwardly V-shaped projections b'''. These V-shaped portions are embellished with rosettes b'''. The flat-sided portion b''' is surmounted by a foliate molding, b'''. The cap C of the newel 40 has moldings c c'. The finial D has an upwardly tapering base, d, ornamented by foliate projections. Above this base d it is ornamented by rosettes d', a superposed molding, d'', a row of small rosettes, d'', and a flaring 45 urn-shaped portion, d'', of foliate configurations.

What I claim as my design, and desire to secure by Letters Patent, is—

1. In a design for a newel-post, the body 50 thereof shaped and ornamented substantially as shown.

2. In a design for a newel-post, the finial D, having base d, ornamented by foliate projections, moldings d'', small rosettes d', rosettes 55 d'', and the flaring urn-shaped portion d'' of foliate configuration, substantially as shown.

HENRY TEXTOR.
